US0D1056880S

(12) **United States Design Patent** (10) **Patent No.:** **US D1,056,880 S**
(45) **Date of Patent:** **** Jan. 7, 2025**

(54) **EARBUD**

(71) Applicant: **LG ELECTRONICS INC.**, Seoul (KR)

(72) Inventors: **Yangtae Kwon**, Seoul (KR); **Hyunjin Park**, Seoul (KR); **Jasoo Cho**, Seoul (KR); **Jeongkeun Choi**, Seoul (KR)

(73) Assignee: **LG ELECTRONICS INC.**, Seoul (KR)

(**) Term: **15 Years**

(21) Appl. No.: **35/519,990**

(22) Filed: **Feb. 3, 2023**

(80) **Hague Agreement Data**

Int. Filing Date: **Feb. 3, 2023**

Int. Reg. No.: **DM/226899**

Int. Reg. Date: **Feb. 3, 2023**

Int. Reg. Pub. Date: **Feb. 9, 2024**

(30) **Foreign Application Priority Data**

Sep. 26, 2022 (KR) 30-2022-0039266

(57)

CLAIM

The ornamental design for an earbud as shown and described.

DESCRIPTION

1.1: Front perspective view

1.2: Back perspective view

1.3: Front

1.4: Back

1.5: Left

1.6: Right

1.7: Top

1.8: Bottom

The broken lines shown in the reproductions depict portions of the earbud that form no part of the claimed design; the shading lines are used to show the surface of the claimed design and do not represent its surface ornamentation.

1 Claim, 8 Drawing Sheets
